UNITED STATES PATENT OFFICE.

WILKES SMITH, OF WACO, TEXAS.

WALL PLUG FOR USE WITH GAS.

Application filed July 26, 1924. Serial No. 728,387.

To all whom it may concern:

Be it known that I, WILKES SMITH, citizen of the United States, residing at Waco, in the county of McLennan and State of Texas, have invented certain new and useful Improvements in Wall Plugs for Use with Gas, of which the following is a specification.

This invention relates to wall plugs especially adapted for use in connection with gas.

Briefly stated, an important object of this invention is to provide a wall plug having a base plate which may be conveniently applied to a base board or any other desired place to effectively conceal the gas valve or cock and to provide a storage space for the hose when not in use.

A further object is to provide a wall plug of the character specified which is of highly simplified construction, neat in appearance, and cheap to manufacture.

Other objects and advantages will be apparent during the course of the following description.

In the accompanying drawing forming a part of this application and in which like numerals are employed to designate like parts throughout the same,

Figure 1 is a perspective of the improved wall plug in use;

Fig. 2 is a front elevation of the improved plug;

Fig. 3 is a detail horizontal sectional view taken on line 3—3 of Fig. 2.

In the drawing, wherein for the purpose of illustration is shown a preferred embodiment of the invention, the numeral 5 designates a wall having a base board 6 which, as illustrated in Fig. 3, is formed with a more or less elongated opening 7. The opening 7 receives the valve or cock 9 of a gas line and is provided with an externally ribbed stem 10 to which a flexible hose 12 may be detachably connected in the usual and well known manner. When the hose 12 is not in use it may be positioned in the opening or compartment 7 and concealed by the closure or door 14 of a base plate 16.

The base plate 16 may be of brass or other metal and extends entirely over the opening 7 and is secured to the base board 6 by means of fastening screws 18 or other suitable fastening devices. The door 14 which is separately and hingedly connected to the base plate 16 as indicated at 20 may be swung to

open position for exposing the hose 12 or for affording access to the handle 22 of the valve 9. It is thus seen that the compartment 7 not only forms a hose receiving means, but also provides a hand hole by means of which access may be had to the handle of the valve. In this connection it is pointed out that the frequent opening and closing of the door for turning the gas off or on will not in any way disturb and possibly loosen the connection of the hose 12 with the stem 10. In other words, the door 14 which when opened affords access to the handle 22, at no time comes in contact with the attaching portion of the hose 12, and consequently the door 14 will not cause a leaky connection between the hose and the stem. Furthermore the door 14 is spaced from destructive or wearing contact with the hose 12 and consequently the hose will not be caused to unravel as the result of frequent opening and closing of the door.

The base plate 16 is also provided with a closure 26 pivotally supported as indicated at 28 and adapted to be arranged directly in front of the outwardly extending stem 10 to which the hose is connected.

In use the hose 12 may be slipped onto the externally ribbed stem 10 and after the door 14 is opened the handle 22 is turned to start the flow of gas to a floor lamp 28 or the like. It is understood, of course, that this invention is not in any way restricted to use in connection with a floor lamp, as it may be used in connection with small gas burners for cooking purposes and for any other purpose found desirable.

The hose 12 may be detached and placed within the compartment 7 if desired or it may be allowed to remain connected to the gas using unit such as the floor lamp. When the outlet is not in use the doors 14 and 26 are closed and will be positioned flush with the outer surface of the base plate 16 and thereby completely conceal the gas valve and possibly the hose.

The improved wall plug which may be said to include the valve 9, the compartment or opening 7 and the base plate 16 may be easily applied to a wall or to the base board without the exercise of unusual skill, and Figure 3 plainly shows that the compartment 7 is extended into the wall 5 a sufficient distance to provide for the manipulation of the handle 22.

Having thus described the invention, what is claimed is:

1. In a wall plug for use with gas, the combination of a valve positioned in an opening in a wall and having a body stem and a valve handle, a base plate extending over said opening and having a door pivoted directly thereon and arranged outwardly of said stem and adapted to be opened to permit a gas hose to be connected to the stem, said base plate being provided at one side of said first named door with a second door directly hinged to said base plate and affording access to the handle of said valve, said second named door being spaced from destructive contact with that portion of the hose which is connected to said stem.

2. As an article of manufacture, the base plate adapted to be extended over a valve receiving opening to conceal the opening and the valve therein and being provided with a hinged door adapted to be positioned outwardly of the valve and opened to permit a gas hose to be connected to the valve, said base plate being provided at one side of said first named door with a second door directly hinged to the base plate and affording access to the handle of said valve, said second named door being spaced from destructive contact with that portion of the hose which is connected to the valve.

In testimony whereof I affix my signature.

WILKES SMITH.
